UNITED STATES PATENT OFFICE.

THOMAS R. WEYANT, OF NEW YORK, N. Y.

WINDOW VENTILATOR.

Application filed October 30, 1922. Serial No. 597,990.

To all whom it may concern:

Be it known that I, THOMAS R. WEYANT, a citizen of the United States, and resident of the city of New York, in the county of 5 Kings and State of New York, have invented a certain new and useful Window Ventilator, of which the following is a specification.

This invention relates to window ventilators of the type wherein a deflector is located upon the window sill, at the inner side of the room, opposite to the lower window sash, and the latter is partially opened; whereby the air enters and strikes 10 the deflector, which directs it upwardly, and the incoming current is in this manner spread over the entire room gradually and evenly, and also uniformly, without causing any draft which is injurious to the occupants.

The principal object of my invention is to provide an improved ventilator of this type, which is simple, inexpensive, conveniently and economically manufacturable, 15 convenient and economical of installation by the user without requiring any skill, conveniently utilizable, strong, rigid and durable, and which when in use may be readily and conveniently detached entirely 20 from its place by the user, and reattached by him when it is desired to return it to its operative position.

Another object of the invention is to provide a ventilator of this type, which is entirely manufacturable and capable of being fitted to any width of window, without requiring any special work or any kind 25 of reconstruction of any part thereof.

Other objects and advantages will herein- 30 after appear.

The invention herein is an improvement upon the window ventilator shown and described in my copending patent application, filed April 14, 1921, Serial No. 461,197.

45 In the accompanying drawings,—

Fig. 1 is a general perspective view showing a ventilator embodying those improvements.

Fig. 2 shows a front elevation of the 50 deflector forming part of this ventilator.

Figs. 3 and 4 are cross-sectional views of the deflector shown in Fig. 2.

Fig. 5 shows a blank form of a detail of the deflector shown in Fig. 2.

55 To the window-frame 1, adjacent to the sill 2, is secured a pair of brackets 3, upon

which is mounted a deflector 4. Said deflector comprises a glass pane 5, and a pair of metallic frames 6, 7, the former of which telescopes into the latter, as shown in Fig. 60 3, the web 6^a of frame 6 slipping into the web 7^a of frame 7. Each of the frames 6, 7 is provided with a sunken flanged portion 8 which bears against the pane 5. The frames 6, 7 are secured to each other by means of 65 bolts 9 passing through the frame 6 and headed nuts 10 passing through the frame 7 and threading over the bolts 9. Upon fastening the bolts 9 and nuts 10 to each other the flanges 8 are caused to firmly grip 70 the pane 5 and hold it in secured position, the springiness of the metal at the bent portions 11 of the frames 6, 7 acting to make the said bolt resilient upon the glass pane, 75 so as to protect the latter against breakage during handling, while affording the firm grip upon the pane.

The deflectors 4 are preferably manufactured in units of 24", 30", 36", 42", etc., to fit widths of windows of standard dimensions. When it is desired to fit windows of uneven or non-standard widths, such as 25", 27", 39", etc., the following means is resorted to. Over each end 12 of the deflector is slipped an extension-member 13, 80 which is channel-shaped in cross-sectional configuration, as shown in Fig. 4, and is made from the blank sheet-metal member shown in Fig. 5. In assembling the deflector 4 with the extension-members 13, the 85 blank, Fig. 5, is bent along the places indicated by the dash and dotted lines 14 to form the channel, and slots 15 formed in said blank are thereby brought into registry with the bolts 9 and nuts 10. The bolts 90 and nuts 9, 10 are then passed through the slots 15 and the frame-parts 6, 7, the members 13 are slid outwardly to extend the length of the deflector to the width of the window to be fitted, and the bolts and nuts 9, 10 are then tightened together, whereby 95 the frame parts 6, 7 and the members 13 are permanently secured together in the adjusted position. The sliding stroke of each 100 of the members 13, relative to the deflector proper, is 2½ inches, by which means the deflector may be extended from one inch to a maximum of five inches beyond the length of the deflector proper, so as to fit it to 105 windows of any width between those of the standard dimensions above mentioned. In as assembling the members 13 a pair of strips

16 thereof at the upper ends of the members are bent over, as shown at 17 Fig. 3, to add strength to the members, and provide a neater appearance of the structure at this 5 place. The edges 18 of the members 13 are bevelled off toward the pane 5 to form a flange thereat which serves to close the space between the walls 19 of the members and the pane.

10 The brackets 3 may be constructed in any suitable manner and preferably in the manner shown and described in my above mentioned pending application. Said brackets are provided with strips 20 having openings 15 21, and the members 13 are provided with stamped out projecting portions 22. When it is desired to mount the deflector 4 in operative position upon the window, the projecting portions 22 are inserted into the 20 openings 21, and the deflector is permitted to drop downwardly, whereupon the circular portions 23 of the stamped portions 22 pass through the circular portions 24 of openings 21 and become positioned beyond 25 the narrow parts 25 of said openings, and in this manner lock the deflector to the strips 20 of the brackets 3.

Variations may be resorted to within the scope of the invention, and portions of the 30 improvements may be used without others.

Having thus described my invention, I claim:—

1. A window ventilator having a deflector, said deflector comprising a pane, a pair of frames for said pane, each of which frames passes completely around the pane, one of said frames telescoping into the other, each of said frames having a sunken flange adapted to hold the pane, and bolts 35 passing through said frames joining them to each other and exerting resilient pressure of said flanges against the pane, and means to attach said frame to and detach it from operative position.

45 2. A window ventilator having a deflector, of means for adjustably extending the length of said deflector including a plate configurated into the form of a channel, the end of said deflector adapted to slide inwardly and outwardly relative to said channel, means to secure said channel at various points thereof to said deflector for adjustably extending said deflector, said deflector having a pane, said channel having bent 50 projecting portions adapted to close up its ends, and said channel having a sunken portion the edge of which is disposed adjacent to said pane.

60 3. A window ventilator having a deflector, said deflector comprising a pane, a pair of frames for said pane, one of said frames telescoping into the other, each of said frames having a sunken flange adapted to hold the pane, bolts passing through said 65 frames joining them to each other and ex-

erting resilient pressure of said flanges against the pane, means for adjustably extending the length of said deflector including a plate configurated into the form of a channel, the end of said deflector adapted to slide inwardly and outwardly relative to said channel, and said bolts passing through said channel for securing the channel at various points thereof to said deflector for adjustably extending said deflector. 70

4. A window ventilator having a deflector, said deflector comprising a pane, a pair of frames for said pane, one of said frames telescoping into the other, each of said frames having a sunken flange adapted to hold the pane, bolts passing through said frames joining them to each other and exerting resilient pressure of said flanges against the pane, means for adjustably extending the length of said deflector including a plate configurated into the form of a channel, the end of said deflector adapted to slide inwardly and outwardly relative to said channel, and said bolts passing through said channel for securing the channel at various points thereof to said deflector for adjustably extending said deflector, and said channel having a sunken portion the edge of which is disposed adjacent to said pane. 80

5. A window ventilator having the combination of side brackets, and a deflector, of means for adjustably extending the length of said deflector including plates configurated into the form of channels, the end of said deflector adapted to slide inwardly and outwardly relative to said channels, means to secure said channels at various points thereof to said deflector for adjustably extending said deflector, and means to removably attach and detach said channels to and from said brackets including pressed-out portions and cut-out portions, and said pressed-out portions being adapted to ship into said cut-out portions and drop downwardly to engage the channels with said brackets. 90

6. A window ventilator having a deflector, said deflector comprising a pane, a pair of frames for said pane, one of said frames telescoping into the other, bolts passing through said frames joining them to each other, means for adjustably extending the length of said deflector including a plate configurated into the form of a channel, the end of said deflector adapted to slide inwardly and outwardly relative to said channel, and said bolts passing through said channel for securing the channel at various points thereof to said deflector for adjustably extending said deflector. 100

Signed at the City of New York, in the county of New York, and State of New York, this 13th day of October, A. D. 1922.

THOMAS R. WEYANT.
